SURGE PREVENTER

Ira Morgan White, Oakland, Calif., assignor to
 The Pelton Water Wheel Company, San Francisco, Calif., a corporation of California

Application March 8, 1941, Serial No. 382,381

10 Claims. (Cl. 137—153)

My invention relates primarily to means for controlling flow in a pipe line, and it is especially concerned with such flow control means utilized in a relatively long pipe line, flow pressure in which is maintained by an electrically driven pump or comparable instrumentality. Devices of this general nature are disclosed in the following patents: 1,995,299, Foulds; 2,038,601, Quick; 2,081,860, Quick; 2,142,410, Quick.

In a pipe line, the inlet of which is supplied by a power driven pump, important considerations are the difficulties which might ensue upon a failure of the power and the resulting return flow of liquid, such as water, within the pipe line. Either this return flow is entirely unchecked and all of the water and the work involved in pumping it are wasted, or in the event check valves are utilized to prevent a free return flow, serious surges or water hammer may take place, possibly being of sufficient magnitude to disrupt either the pipe or the attendant fittings. It has heretofore been proposed to provide in an appropriate part of the pipe line an opening controlled by a valve, and to open such valve when the power of the pump fails. This permits a check valve to be utilized and a return flow to take place through the opening. Then the return flow is throttled and stopped as quickly as possible in order to avoid water waste, but sufficiently slowly to avoid excessive strain. This type of arrangement is termed a "surge suppresser" and most often depends upon the pressure of the fluid in which the surge is being suppressed for operating power. Also, if the disturbing condition ceases prior to complete operation of the suppresser, the suppresser valve returns to its original closed condition, although a surge may have been initiated in the pipe line and may not have been thoroughly damped out before the suppresser closes. Further, the surge which occurs in a specific or particular pipe line is found to be substantially characteristic of that pipe line, which would indicate that a special surge suppresser should be made for each particular installation.

In accordance with my invention, however, I provide a structure which will operate prior to the occurrence of any excessive pressure and is hence more properly a surge preventer. It is also an object of my invention to provide a surge preventer which is substantially a standardized product for economy in manufacture, but which is subject to installation adjustment in a particular pipe line to respond exactly to the characteristics of that specific pipe line.

Another object of my invention is to provide a

surge preventer which necessarily must proceed through a complete cycle of operation once its operation has been initiated.

A further object of my invention is to provide a surge preventer which operates to relieve the pressure on the pipe line for a predetermined time period, at least, whether or not the disturbing factor continues for the predetermined time.

A further object of my invention is to provide a surge preventer generally useful in pipe lines.

An additional object of my invention is to provide a surge preventer especially adapted for use in pipe lines served by electrically driven pumps.

While the foregoing are the principal objects of the invention, others are included in the following description and are apparent from the structures illustrated in the accompanying drawings, in which

Fig. 1 is a side elevation (part of a casing being removed) of one form of surge preventer in accordance with my invention.

Fig. 2 is a cross-section, the plane of which is indicated by the lines 2—2 of Fig. 1.

Fig. 3 is a detailed cross-section, the plane of which is indicated by the lines 3—3 of Fig. 1.

Fig. 4 is a cross-section, for the most part on a vertical axial plane, through the surge preventer of Fig. 1.

Fig. 5 is an axial cross-section on an enlarged scale of part of the auxiliary valve mechanism of the surge preventer.

Fig. 6 is a view similar to Fig. 5, but showing the auxiliary valve in open position.

Fig. 7 is a plan of the control mechanism of the surge preventer.

Fig. 8 is a side elevation of the structure shown in Fig. 7.

Fig. 9 is a cross-section, the plane of which is indicated by the line 9—9 of Fig. 7.

Fig. 10 is a diagram showing the surge preventer installed and in its normal closed position.

Fig. 11 is a diagram similar to Fig. 10, but showing the surge preventer in opening position.

Fig. 12 is a diagram similar to Figs. 10 and 11, but showing the surge preventer after it has attained its full opened position and is returning at an excessive rate toward closed position.

Fig. 13 is a side elevation, portions being shown in cross-section on a vertical axial plane, of a modified form of surge preventer.

Fig. 14 is a view similar to Fig. 7, but showing the modified form of control structure in cross-section, the planes of which are indicated by the lines 14—14 of Fig. 13.

Fig. 15 is a cross-section, the plane of which is indicated by the lines 15—15 of Fig. 14.

Fig. 16 is a detail cross-section, the plane of which is indicated by the lines 16—16 of Fig. 14.

Fig. 17 is a fragmentary cross-section of the modified dashpot structure.

Fig. 18 is a diagram of a surge preventer of somewhat modified form applied to a different type of liquid release valve.

Fig. 19 is a side elevation, portions being in a cross-section, of some of the controls utilized with the structure of Fig. 18.

In its preferred form, the surge preventer of my invention includes a valve for releasing water or other liquid from a pipe line in which the valve is installed, and which valve is provided with means for causing the valve to open upon the occurrence of a predetermined condition, such as a power failure, and for returning the valve from open to closed position, but only after the valve has once attained its fully opened position, and then only at a rate which is not more than a predetermined rate of return.

In the principal form of my invention the installation is customarily made as shown in the patents above-enumerated and in which a pump 6 (Fig. 10) supplies fluid to a long pipe line 7, through a return check valve 8 close to the beginning of the pipe line 7. A surge preventer, generally designated 9, is installed to provide an outlet 10. The pump 6 is driven by an electric motor 11, included in a suitable circuit 12 from any source of power 13. Normally and when conditions are entirely favorable, the motor 11 operates continuously, thereby pumping fluid continuously into the line 7. If, however, the power to the motor 11 is interrupted, the pump 6 decreases speed, the flow in the pipe line 7 slackens and reverses ultimately closing the check valve 8. In accordance with my invention the surge preventer 9 comes into operation as soon as power to the motor 11 fails. Furthermore, even though the power should promptly be restored, the surge preventer nevertheless goes through a complete cycle of operation.

In one preferred form (Figs. 1 to 12, especially) my surge preventer 9 includes a valve body 16 which has an inlet opening 17 to the pipe line 7 and a discharge opening 18 to the outlet 10. Within the valve body there is provided an annulus 19 serving as a valve seat and extended to provide the walls 20 of a cylindrical chamber 21 positioned by a closure cap 22, secured to the valve body 16. Adapted to operate within the cylindrical chamber 21 is a piston 23 having a sealing means 24 therearound and being extended at a reduced diameter to terminate in a conical valve 26 adapted when in one extreme position to abut or seat upon valve seat 19. In another extreme position the valve 26 is retracted to be spaced from the valve seat 19 and to be disposed in streamline continuity with the outer contour of the chamber walls 20 to afford free communication between the inlet 17 and the discharge opening 18, which communication is blocked when the valve is closed.

The piston 23 and therefore also, the valve 26 are moved in accordance with certain differential pressure conditions, some of which exist on opposite sides of the piston 23. For this reason intermediate the packing 24 and valve seat 26, the reduced piston body is provided with a cylindrical portion 27, slideably disposed within a reduced cylindrical collar 28 at the lower portion of the chamber wall 20, so that between the collar 28

and the packing 24 there remains an annular chamber 29 which communicates with the inlet 17 through a passageway 30. In this fashion the lower face of the piston 23 is always subject to the pressure within the pipeline 7, which therefore tends to move the piston 23 and the valve 26 toward open position. In the event the opening pressure is resisted by a greater pressure, the valve 26 remains closed, or is moved from open position toward closed position. In the event the force acting downwardly upon the upper face of the piston is less than the force within the annular chamber 29, the piston and valve 26 either move toward open position or remain in open position. Part of the pressure upon the valve member is upward pressure acting upon the lower surface of the valve 26 within the confines of the seat 19 and this pressure augments the pressure within the annular chamber 29, but by varying the pressure within the chamber 21, I control the movement of the piston 23 and valve 26.

Pressure liquid for the chamber 21 is supplied from any suitable source and is preferably derived from the line 7 near the outlet of the pump 6 and passes through a pipe 31 including a filter 32 into a relay valve housing 33, which is connected by a nipple 34 having a circular cylindrical bore 36 to a boss on the cap 22 (see central portion of Figure 1 and also detail shown in Figure 3). Operating within the bore 36 is a plunger 37 having a freely sliding fit and allowing some leakage to take place from the pipe 31 around the plunger 37. From the bore 36 below the plunger 37, flow is through a drilled passageway 38 to the interior of the chamber 21. Whatever leakage may occur past the packing 24 to deplete the chamber 21 is made up by liquid leaking past the plunger 37 so that normally the pressure within the chamber 21 is fully maintained. When, however, pressure within the bore 36 above the plunger 37 drops for any reason by failure of the motor 11, the plunger 37 is displaced upwardly from its closed position as shown in Fig. 3, until it abuts an adjusting screw 38 piercing the body 33 and locked in position by a nut 39 protected by a cap 41.

The position of the adjusting screw 38 governs the extent of travel of the plunger 37 and correspondingly controls the annular area of communication between the interior of the bore 36 and the interior of a pipe 42 coaxial with the nipple 34 and establishing communication with a duct 43 leading to waste, so that upon reduction of pressure within the upper portion of the bore 36, the plunger 37 rises to the adjusted amount and the liquid within the chamber 21 passes out through the ducts 38 and 43 to waste; the speed of such flow being regulated by the position of the adjusting screw 38. The valve 26, upon reduction of pressure within the bore 36, is no longer blocked by liquid trapped within the chamber 21, but under the pressure existing within the annular chamber 29 is free to move from its extreme closed position toward its extreme open position. Upon reestablishment of pressure within the upper portion of the bore 36, however, the plunger 37 is restored to its position seated upon the pipe 42, no more liquid can escape from the chamber 21 through the passages 38 and 43 so that the leakage past the plunger 37 replenishes the chamber 21 and the valve 26 is again urged towards its seat 19.

Since the pipe 31 is connected to what amounts to a constant liquid supply, the pressure condition existing within the bore 36 depends upon dis-

charge conditions. Connecting with the bore 36 is a discharge pipe 46 which extends to a relief valve, generally designated 47. This valve has an upper chamber 48 into which the pipe 46 extends and a lower chamber 49 connected by a duct 50 to a waste elbow 51 in the cap 22 (see Figure 9). Between the chambers 48 and 49 is a valve seat 52 upon which is adapted to be seated a valve 53 operated by a stem 54 projecting from the housing 47 and leakage along which is precluded by a packing 56. An abutting screw 57 pierces the bottom of the chamber 49 and is held in position by a locknut 58 so that the amount of opening and the area for flow over the valve seat 52 is regulated by abutment of the valve 53 with the adjusting screw 57. When the valve is closed or seated no flow can occur through the conduit 46, and hence the pressure within the bore 36 above the plunger 37 remains equal to that in the pipe 31. When, however, the valve 53 is opened, the pressure within the bore 36 drops permitting the plunger 37 to lift and the chamber 21 to be exhausted, since the area for flow over the valve seat 52 is greater than the area of flow through the pipe 31. By suitably setting the adjusting screw 57, the rate at which the plunger 37 can rise is regulated. Thus, the position of the valve stem 54 through the relay valve 33 determines whether or not the valve 26 opens.

Apart from its functions as a surge preventing valve, the valve 26 can be opened to release liquid from the pipe line 7 at times, to act as a pressure regulator. For this added function, pressure from the controlling source, such as the pipe 7 is communicated through a duct 59 to a standard pressure-responsive flow controller 60 located in a drain line 61 extending from the upper part of the bore 36 to the drain elbow 51. When the controlling pressure is low or normal, the regulator prevents flow through the drain line 61, or permits flow not greater than the influx through pipe 31. But when the controlling pressure is excessive, the regulator 60 opens the drain line 61 so that the upper bore 36 connects to the drain elbow 51, the pressure above the plunger 37 falls, and the valve 26 opens, as before. Upon restoration of the controlling pressure to normal value, the regulator 60 closes the drain line 61 and the plunger 37 is restored to its seat so that valve 26 closes.

A similar effect can at any time be produced by hand upon manual operation of a spring urged control button 62 which, when operated opens the controller 60 so that flow from the upper bore 36 persists as long as the button is held depressed, but conditions are restored when the button 62 is released. The valve 26 can thus be manually opened partially or entirely.

In order to actuate the valve stem 54, I preferably arrange it so that the valve stem is responsive to a failure of power in the circuit 12 to the motor 11, so that instantly there is a failure of power the surge preventer begins to operate. For that reason at a convenient point in association with the housing 47 and preferably on the same mounting plate 63 therewith, I mount an electro-magnet 64, the field coil of which is disposed in the circuit 12 with the motor 11 and is energized and deenergized in synchronism therewith. The movable armature 65 of the electro-magnet is connected by a pivoted link 66 to a dual lever 67, one extremity of which is connected by a pivot pin 68 to an adjusting fitting 69, located on the top of the stem 54. Adjacent to the pivot 68, the

dual lever 67 is provided with an extended fulcrum pin 70. This fulcrum pin is normally engaged by twin latch hooks 71 having a common hub and swinging on an axle 72 supported on a headplate 73, which also seals the valve housing 47. The fulcrum pin 70 is urged against the latch hooks 71 by a coil spring 74 abutting a collar body 76 connected by a pivot pin 77 to the dual lever 67. The spring 74 also abuts an adjusting thimble 78 screwed into the base plate 63 and held in position by a locknut 79 so that by adjusting the thimble 78 the effect of the spring 74 can be varied.

The relationship of the various pivots is such that normally when the electro-magnet 64 is energized to contain the armature 65 as it is during customary operation and the fulcrum pin 70 is effective, the spring 74 is compressed and the valve 53 is held on its seat 52. When, however, the magnet 64 is deenergized, the spring 74 is then effective to rotate the dual lever 67 clockwise, as seen in Fig. 9, around the axis of the fulcrum pins 70 to move the valve stem 54 downwardly to open the valve 53 as far as the adjusting stem 57 will permit. Thus, when there is a power failure the valve 53 is immediately opened. This, through the previously described connections, initiates an opening movement of the main valve 26.

Adapted generally to be translated with the piston 23 and the main valve and mounted in connection therewith, is a valve stem tube 91 surrounding a rod 92 (Fig. 5) which at its lower end is threaded into a reduced fitting 93 secured by threads 94 in the valve body 27. The fitting 35 is pierced by passages 96 and 97, which latter merges with a passage 98 in the valve body so that all of the passages together form a conduit between the interior of the chamber 21 and the outlet 18 of the valve body. Flow through such conduit is, however, subject to the relative position of the tube 91, the lower end of which is provided with a cooperating seat 99 within the lower end of the body 27, so that when the tube 91 is seated thereupon no flow takes place 45 through the conduit, whereas when the tube 91 is away from its seat, flow can be freely effected. In order normally to hold the tube 91 in closed position, it is provided with an interior washer 101, seated on an abutment within the tube and forming a support for a closure spring 102. The spring also presses against an adjusting nut 103 accessible through an aperture 104 in the side of the tube 91 and engaging the upper threaded end of the rod 92. By turning the nut 103 the pressure with which the tube 91 is held on its seat 99 is varied. The tube 91 passes through the cap 22 and is provided with a packing 106. Just above the packing, when the parts are all in closed position, are apertures 55 107 piercing the tube 91. Any leakage therefore which passes within the tube 91 goes out through the apertures 107 to a center depression 108 in the cap 22 from which it escapes through a drainage connection 109.

Joined to the upper end of the valve tube 91 is an extension stem 111 passing upwardly through a stuffing gland 112 in the lower head 113 of a dashpot cylinder 114. This structure is supported by a spider 116 from the cap 22. Disposed within the dashpot cylinder 114 is a dashpot piston 117 fast on the extension stem 111 so that the tube 91 moves in unison with the movement of the piston 117. The upward movement of the piston 117 within the cylinder 114 is virtually unhampered, since the piston is pro-

vided with a pair of check valves 118, each of which has a spring 119 normally effective to close it. When the check valves open, fluid flows from the cylinder 114 above the piston through passages 121 controlled by the valves to the cylinder 114 below the piston. The direction of opening of the valves 118 is such that the ascending movement of the valve 26, which causes the tube 91 to rise in concurrence therewith, is virtually unhampered.

However, descending movement is restricted by the dashpot, since upon return movement of the piston 117, the valves 118 are closed and the lowering travel is subject to the rate at which fluid can pass from the cylinder 114 beneath the piston 117 to the cylinder 114 above the piston. This flow is preferably through a conduit 122 containing a regulating valve 123, which can be set as desired so that the rate at which the tube 91 descends is governed by the setting of the dashpot regulator. If the piston body 27 should descend faster than the dashpot permits the stem 111 to descend, the spring 102 (Fig. 5) is compressed, the tube 91 leaves its seat 99, the fluid flows from the chamber 21 out through the conduit comprised of the passages 96, 97 and 98. The pressure within the chamber 21 is therefore reduced to retard the closing movement of the piston body 27 until the dashpot descends farther to lessen the compression of the spring 102 so that the tube 91 is again seated and the pressure in the chamber 21 forces the piston 23 further to descend. In this fashion the dashpot which is interposed between the main valve body 27 and the valve stem 91 is effective to govern the rate of closure of the main valve. This rate is therefore set or established independently of operating pressure and can only be varied by altering the adjusting valve 123 in the conduit 122.

The rod 111 projects through an upper closure plate 124 on the dashpot cylinder 114 to elevate a stem 126, on which is a collar 127 (Fig. 8). As the stem rises, the collar approaches an arm 128 merging with the boss of the latch levers 71. When the collar 127 abuts the arm 128 and continues to rise, the latch levers 71 are rotated against the urgency of a spring 129 secured to the arm 128 until the fulcrum pins 70 are released and the spring 74 is promptly effective to close the valve 53 as previously described. As soon as the collar 127 begins to descend, the spring 129 tends to restore the latch levers 71, but the ends of these abut against the pins 70 until the electromagnet 64 is again energized whereupon the latch levers 71 again hook onto the pins 70.

Also operating in conjunction with the operation of the lever arm 128 is an electric switch 131. When there is a power failure the switch trips and the circuit cannot again be closed until the switch is reset, and since resetting cannot occur until the valve 26 has achieved its extreme open position, there is assurance that the valve will open fully and complete a cycle even though the power interruption may be but momentary. On the arm 128 I provide a boss 132 against which a pair of adjusting nuts 133 abut. These are on the upper end of the rod 134 extending to an arm 136 to which the rod is pivoted by a bolt 137. The arm 136 is connected by a pivot pin 138 to the base 63. Also mounted on the pin 137 is a link 139 connected by a pivot 141 to an actuating arm 142 of the switch 131. A spring 143 normally urges the arm 142 in one direction.

Within the electric switch 131 freely rocking on

the pivot 144 is a plate 146 carrying a standard mercury switch 147 in series circuit with the electro-magnet 64 and with a magnet 148 which, when energized holds an armature 149 and the switch 147 in a circuit closed position but unbalanced to the right (Fig. 8). When the power fails, the magnet 148 is also deenergized, the armature 149 is no longer attracted thereto and the plate 146, being unbalanced, rotates to the right until the mercury switch 147 opens the circuit and also a stop pin 151 carried by the plate 146 abuts the arm 142. Any restoration of power before the mercury switch 147 is reclosed is ineffective upon the magnet 64. The switch 147 is therefore reclosed when the valve is freely open and hence a complete stroke is assured. When the collar 127 approaches its upper range of movement and lifts the arm 142, the abutting pin 151 also rotates the plate 146 through a central position and until it is unbalanced to the left (Fig. 8) and rests against a stop pin 152 with the mercury switch 147 in closed position. Thus the circuit to the magnet 64 and to the electro-magnet 148 is reclosed just as the collar 127 and the valve achieve their uppermost positions. As the collar 127 descends, the arm 142 returns to its normal position under urgency of the spring 143, but the plate 146 remains in unbalanced position to the left. When the power is subsequently restored the magnet 64 and the electro-magnet 148 are re-energized so that the armature 149 is again attracted to move the plate 146 back to an unbalanced position to the right, but with the mercury switch 147 still closed.

In accordance with this arrangement, therefore, the surge preventer is immediately put into action as soon as there is a power failure and completes its opening stroke whether the power failure is momentary or is protracted. As soon as the valve has been fully opened, however, the latch levers 71 are tripped off, and conditions are put into effect for again closing the valve, which is returned at a rate not to exceed a predetermined rate since any excess movement of the valve produces an opening of the conduit formed by the apertures 96, 97 and 98 to release excess closing fluid. Thus, the valve finally seats itself at the predetermined rate and the system is restored to normal.

In some installations a modified form of surge preventer is utilized, the general conditions of installation being substantially the same as previously described, but the particular form of the valve and immediately associated mechanism being somewhat altered. In this arrangement there is provided a valve housing 161 having an inlet connection 162 and a discharge opening 163. Within the valve housing is a valve seat 164 removably held in place by fastenings 166 and which seat is continued to provide a differential diameter cylinder 167 having an opening chamber 168 and a closing chamber 169, between which a piston 171 of a valve body 172 is disposed. A valve cone 173 completes the lower end of the valve body and is adapted to cooperate with the seat 164 to effect closure and opening of the passageway extending between the inlet 162 and the outlet 163.

Fastened to the piston 171 and the valve body 172, there is a valve stem 176 which is constructed exactly as is the valve stem shown in the preceding figures and which pierces a sealing gland 177 in the closure cap 178 of the valve housing 161 and extends through an intermediate generally circular chamber casing 179 resting upon

the cap 178. A dashpot cylinder 181 closed by a sealing cap 182 is supported on the casing 179. In this arrangement the pressure on the inlet 162 tends to force the valve open or upwardly and simultaneously to lift the stem 176. But this movement is ordinarily blocked, since the chamber 169 is normally filled with liquid under pressure. To supply the chamber 169 there extends from a source of fluid under pressure such as the pipe line in which the valve is installed, a pressure pipe 183 from which a branch pipe 184 extends to an outlet 186 communicating with the interior of the chamber 169 and normally maintaining such chamber full of liquid. Since the area under pressure above the piston 171 is considerably in excess of the area of the exposed valve face 173, and since the intermediate chamber 168 is normally in communication with a drain pipe 187, in the usual case the valve is held closed.

Also in communication with the chamber 169 is a duct 188 a portion of which is cast within the intermediate body 179 and which merges with a pilot valve chamber 189 within which is disposed a cylindrical sleeve 191. Within the sleeve a valve piston 192 is adapted to reciprocate and includes a valve cone 193 cooperating with a valve seat 194 included in the cylinder 191, and disposed between the interior of said cylinder and a drain connection 196 which extends to any region of low pressure. A passageway 198 when open affords communication between the drain 196 and between a chamber 199 above the piston 192 in effect, and within the cylinder 191, but ordinarily communication through such passage 198 is blocked by a plunger valve 201, which is provided with a valve cone 203 adapted to seat upon the interior of the valve piston 192.

The plunger 201 extends through a packing 204, held in place within the housing 189 by a closure cap 206 and connected by an adjusting nut and threaded connection 207 to a fitting 208, the axial travel of which is limited by an adjusting screw 209 threadedly engaging the wall of the casing 179 and adjustably locked into position by a cap 211.

Pivotedly connected to the fitting 208 by a pin 212, is a dual lever 213, which at its opposite end is connected by a pin 214 to a follower 216. One end of the follower is drilled to ride upon a guide pin 217 projecting inwardly from the wall of the casing 179, while the other end of the member 216 is connected by a pin 218 to the movable armature 219 of an electro-magnet 221 mounted within a casing 222 on the sidewall of the housing 179. The electro-magnet 221 is so introduced into the electric circuit of the power supply for the pressure source of the line in which the valve is disposed, that when the power is on and conditions are normal the solenoid 221 is energized and maintains the parts in the position shown in Fig. 15.

Against the effect of the energized electro-magnet 221 a coil spring 223 exerts its force. This spring at one end is connected to an eyelet 224 fastened in the dual lever 213, and at its other end projects through a suitable aperture in the casing 179 and is connected to an adjusting structure 226 so that the tension of the spring 223 can be established or varied.

Also a part of the dual lever 213 is a fulcrum pin 227 which has a lost motion engagement with a pair of fulcrum hooks 228 which are secured to a common hub 229 mounted by a pivot rod 231 in the casing 179. An extension lever 232 pro-

jects from the hub 229 and terminates in a threaded member 233 into which is screwed a stem 234 held in adjusted position by a lock nut 236. The upper end of the stem 234 carries an abutment washer 237 in the path of a collar 238 situated on the valve stem 176.

In the operation of this structure as so far described the parts are normally in the position shown in Fig. 15, but when a power failure occurs the electro-magnet 221 is deenergized so that the spring 223 is effective immediately to rock the dual lever 213 about the pin 227 of the fulcrum, thereby translating the plunger 201 axially toward the right in Fig. 15 and against the adjusted stop 209. This movement of the plunger valve opens the passageway 198 between the chamber 199 and the drain outlet 196. Since the chamber 199 has previously been filled by leakage around the periphery of the piston 192 from the passageway 188, the valve 192 theretofore has been held upon its seat, but upon availability of the passageway 198 for escape of the pressure liquid theretofore entrapped, the pressure of the liquid within the passageway 188, and of course in the chamber 169, is effective to unseat the piston valve 192 translating it to the right in Fig. 15 so that the piston valve 192 follows the operation of the plunger valve 201 and itself opens free communication between the passage 188 and the drain opening 1906, thereby permitting the pressure of the pipe line fluid acting through the inlet 162 and against the lower face of the valve cone 173 to displace the entire valve body 172 upwardly as seen in Fig. 13, forcing the previously entrapped liquid in the chamber 169 out through the drain opening 196. The rate at which this displacement can occur is regulated by the screw 209 which serves as a stop, not only for the plunger valve 201, but also for the piston 192 and thereby limits the maximum area of the passageway between the duct 188 and the drain opening 196. Consequently, upon the occurrence of a power failure, the valve body 172 initiates travel from closed position toward open position.

In order as in the previous instance, to insure that even though the power failure is but momentary, the travel of the valve 172 will be a complete stroke from closed position to fully opened position, I dispose within casing 179 an electrical switch 241 which is included in an appropriate circuit with the power supply and is normally in closed position. On the valve stem 176 just below the collar 238 is a secondary collar 242 which when the valve is closed rests against a spring arm 243, just out of contact with a controlling plunger 244 regulating the position of the switch 241. As soon as the stem 176 starts its upward movement, the collar 242 rises out of abutment with the spring 243, which due to its resiliency then presses against the plunger 244 to open the switch 241. Thus, as long as the collar 242 has risen away from its closed position and until it returns to its closed positions, thereby stressing the spring 243 and relieving the pressure upon the stem or abutment 244, the switch 241 remains open and even a restoration of power while the switch 241 is open is ineffective to return the parts to original position.

Consequently, once the opening movement of the valve has been initiated, it continues for substantially its entire stroke and at least until such time as the collar 238 rises into abutment with and carries with it the washer 237. This washer

being adjustable, the abutment position can be arranged to occur within a wide range adjacent the upper limit of the valve stroke. When the washer 237 is lifted it simultaneously rotates the extension 232. One effect of this is to relieve the previously maintained pressure upon the plunger 246 of a normally closed electric switch 247, which is appropriately included in the power supply circuit, and which is opened as soon as the extension 232 is lifted.

The movement upwardly of the extension 232 also rotates the hub 229 and lifts the fulcrum latches 228 off of the fulcrum pin 227 so that the spring 223 is effective to urge the plunger valve 201 axially toward the left in Fig. 15 thereupon closing it against the piston 192 and also urging the piston itself axially toward the left in Fig. 15 so that communication between the passage 188 and the drain 196 is interrupted. The chamber 169 at all times is connected to the pressure supply from the pipe 183 by the pipe 184 and the aperture 186 so that upon blocking of the means of liquid escape by seating of the piston valve 192 and the plunger valve 201, the chamber 169 refills with pressure liquid, and since its area is greater than that exposed to the pressure within the inlet pipe 162, the valve 172 is returned to seating position.

The rate of return of the valve is established at a value which cannot be exceeded by the provision of a dashpot piston 251 operating within the dashpot cylinder 181. This piston 251 is connected to a pilot valve within the main valve 173 exactly as described in connection with Figs. 1 to 12 inclusive, although the construction of the dashpot piston itself is somewhat different in order to avoid external piping and external adjustment.

In the present modification the piston 251 which is secured to the valve stem 176 and which divides the cylinder 181 into an upper chamber 252 and a lower chamber 253 is provided with a poppet or unbalanced valve 254 controlling flow through a passage 256 affording communication freely between the chambers 252 and 253. The valve 254 is normally urged seated by a spring 257 which is tensioned by an adjusting nut 258 on the valve stem and is arranged so that when the piston 251 rises, the valve 254 opens readily and affords free communication between the chambers 252 and 253 imposing substantially no restriction therefore on the movement of the main valve 172. Yet upon return or lowering movement of the piston 251, the valve 254 seats, blocking communication through the passageway 256 so that ordinarily but little or no flow could occur from the chamber 253 back into the chamber 252. A passageway 261 extends from the chamber 253 to the chamber 252, the flow through which is regulated by a threaded needle valve 262 locked in an adjusted position by a pinch stud 263. Adjustment of the needle valve is possible only by removing the closure 182 of the dashpot cylinder so that tampering is unlikely. The adjustment of the needle valve 262 is preferably set at any value which will regulate the flow returning from the chamber 253 to the chamber 252 in such a fashion as to afford the desired rate of return of the main valve body 172 from its fully opened position to its fully closed position. Preferably an indicator rod 264 extends from the stem 176 and projects from the cap 182 to give a visual indication of the position of the valve 172. The liquid within the dashpot cylinder 181 is replenished from an external supply tube 266.

Under the control of the dashpot structure

therefore, the valve 172 after attaining its open position returns at a controlled rate or not faster than a predetermined rate to its closed position. Whenever the power is restored the solenoid 221

5 is reenergized attracting the armature 219 back into the position shown in Fig. 15 and rocking the dual lever 213 to retension the spring 223. Shortly after the valve stem 176 has descended from its maximum upper position the upper collar 10 238 drops below the washer 237 thereby permitting the free ends of the latch levers 228 to ride upon the pins 227. If the solenoid is then energized the latch levers 228 drop over the fulcrum pin 227 again, restoring those parts to their original condition and the extension lever 232 recloses the switch 247 so that the main power can be restored. But if the solenoid should be disabled, the switch 247 is not then reclosed and the main power cannot be restored until the trouble is 15 rectified. Finally, just as the valve 172 closes, the secondary collar 242 again contacts its spring 243 so that the switch 241 is restored to its normally closed position. The mechanism therefore is 20 ready for functioning again upon occurrence of a similar power failure.

In addition to its function as a surge preventer in the pipe line upon occurrence of a power failure effective upon the electromagnet 221, the structure may also be utilized as a device which will 25 relieve excessive pressure in the pipe line upon occurrence of a pressure therein greater than a predetermined value. For that reason, on the pressure supply line 183 which is connected to the pipe line, an extension 271 is provided leading to 30 a standard spring pressed and adjustable pressure relief valve 272, which is set at any predetermined value of pressure. Upon the occurrence of an excessive pressure the valve 272 is thereby opened, and permits fluid to flow from the extension 271 into a connection 273 extending into one end of a bore 274 disposed adjacent the valve seat 194 and the drain outlet 196. Situated within the bore 274 is a piston 276, one face of which is 35 therefore subjected to pressure within the pipe 273, and the other face of which is exposed to the substantially lower pressure in the drain opening 196, but being also connected by a stem 277 to the plunger valve 201.

With this arrangement, as soon as an excessive 40 pressure occurs in the pipe line and as soon as the valve 272 opens, fluid passes through the pipe 273 and presses against the piston 276, translating it toward the right in Fig. 15 against the urgency of the spring 223, and unseats the plunger valve 201. This unseating of the plunger valve causes the piston valve 192 to open as previously described and permits the chamber 169 to exhaust to the drain 196, thereby opening the valve 173 as previously described.

Immediately, however, upon reduction of pressure in the main pipe line below the predetermined value, the valve 272 closes, further communication with the piston 276 is disrupted and due to leakage around the piston, the pressure 45 equalizes on opposite sides thereof so that the spring 223 is again effective on the dual lever 213 to retranslate the plunger 201 back to its seated position and to carry with it the piston valve 192, the lost motion arrangement between the fulcrum pin 227 and the latch hooks 228, permitting this operation. As soon as the plunger valve 201 and the piston valve 192 are reseated, the chamber 169 is again filled with pressure fluid and the main valve 173 is reseated in closed position, this movement also being under the general control of the

dashpot 181 as to rate, but being entirely independent of the electrical circuit since the electromagnet 221 remains energized at all times.

The surge preventer is further modified under different conditions of installation, particularly for use with a Larner-Johnson type of valve. In this installation which is illustrated partially diagrammatically in Figs. 18 and 19, a pipe line is provided with a relief pipe 301 which merges with the outer casing 302 of the Larner-Johnson valve, generally designated 303, and which outer casing merges with a discharge duct 304. Within the casing 302 and coaxial therewith is a cylinder housing 306 defining a chamber 307, separated from a chamber 308 by a piston 309, to which is joined a valve cone 311 adapted when closed to seat on a seat 312, located between the interior of the housing 302 and the duct 301, so that when the valve is closed flow outwardly from the pipe line is blocked, although when the valve is open such flow takes place readily. The chamber 308 is normally connected to the exterior of the housing 302 by a duct 310 and is normally subject to atmospheric pressure, while the chamber 307 is subject to pipe pressure within the duct 301. This latter connection is accomplished by a pipe 313 which extends through a fixed orifice 314 to the interior of a housing 316 merging with the interior of the chamber 307. Since the area above or to the left of the piston 309 is considerably greater than that below the piston within the chamber 308, the valve 311 is normally urged closed.

Mounted on the piston 309 is a rack 317 with which meshes a gear 318 on a shaft 319, extending through the housing 316 and passing through a packing gland 321 and terminating in a fitting 322 for the installation of a lever for manipulation of the structure. Also on the shaft 319 is a gear 323 meshing with a rack tube 324 constrained to axial movement by a telescopic connection with a rod 326. The telescopic or lost motion connection comprises a pin 327 extending diametrically through the rack tube 324 and running in a slot 328 in the rod 326, the end of the slot being defined by an adjustable abutment stud 329 held in adjusted position by a lock nut 331, so that the extent of lost motion between the rack 324 and the rod 326 may be adjustably established. In accordance with this arrangement all movements of the piston 309 are reflected in the rack tube 324 either in equivalent or proportional amount, depending upon the gearing.

In this arrangement, as in the preceding ones, there is provided a solenoid 331, which is included in a suitable circuit with the source of power and which is mounted in a suitable housing 332. The solenoid is ordinarily energized and retains in upper position an armature 333, which is urged downwardly toward a stop 334, by a spring 336 which engages a pin 337, extending from a lever 338 connected by a pivoted link 339 to the armature 333. The spring is anchored by an adjustable bolt 341 held in position on a mounting bracket 342 by adjusting screws 343. The lever 338 also is provided with fulcrum pins 344 fitting in slots 346 in the bifurcated end of a mounting rod 347 stationarily disposed on a valve housing 348. A sliding washer 349 encompassing the stem 347 is urged upwardly against arcuate faces on the lever 338 by a coil spring 350, but resulting upward movement of the lever is restrained by a latch lever 351 at its lower end connected by a pivot 352 to the stationary

mounting 348, and at its upper end normally urged into engagement with a pin 353 on the lever 338 by a coil spring 354 connected to a stationary support 356.

When the power to the solenoid 331 fails, the coil spring 336 is effective to lower the armature 333 and to rock the lever 338 about the fulcrum pin 353, simultaneously slightly depressing or compressing the spring 350. Partaking of this movement of the lever 338, is an adjustable valve stem 361 connected by a pin 362 to the lever 338 and connected to a valve plunger 363 extending through a packing gland 364 at the upper end of a valve housing 348. The valve stem 363 has a reduced portion 366 adjacent which a pipe 367 merges with the interior of the valve housing 348, the pipe being provided with an adjustable orifice 368 and extending to a connection 369 with the interior of the chamber 316. Thus, communication is established from the chamber 307 through the adjustable orifice 368 to the interior of the valve housing 348, above a poppet valve 371, closing the lower end of the chamber and controlling communication between the pipe 367 and a drain connection 372.

When the lever 338 is translated downwardly upon interruption of power to the solenoid 331, the valve plunger 363 is likewise depressed, opening the valve 371 and affording communication from the chamber 307 to the drain 372, but only through the restricted orifice 368. The size of the orifice 368, however, is always adjusted to an area greater than that of the fixed orifice 314, so that the liquid otherwise trapped within the chamber 307 is free to flow out of the drain when the valve 371 is open, but the rate of discharge of such liquid is governed by the adjustable orifice 368, so that the opening of the valve 311 due to the superior pressure existing within the conduit 301 is at an established rate. Consequently, immediately the valve 371 is opened the valve 311 starts its opening movement and the rate thereof is governed by the position of the adjustment 368.

In a similar fashion to the preceding modifications, provision is made for preventing an immediate restoration of power returning the valve to its closed position prior to the time it has made a full stroke or a complete cycle. Appropriately included in the electrical circuit are contacts 373 and 374, the latter of which is preferably mounted on the rack tube 324, so that as soon as the valve 311 starts to open, the contacts 373 and 374 are separated, thereby opening a circuit so that subsequent restoration of power prior to the time the valve returns to its closed position is ineffective to reenergize the solenoid 331, which therefore necessarily remains in open position all of the time that the valve 311 is off of its seat.

As the valve 311 during its opening movement approaches its maximum open position, the lost motion connection between the rack tubes 324 and 326 is taken up so that the pin 327 abuts the adjusting stud 329, and the rod 326 is then translated along with and in unison with the rack tube 324. The rod 326 is connected by a pivot pin 376 with the lever 351, so that as the valve achieves its fully opened position, the lever 351 is rocked on its pivot 352 against the urgency of the spring 354 to release the fulcrum pin 353. The effect of such release is to permit the relatively strong spring 350 to drive the pin 344 and the lever 338 in a generally upwardly direction to lift the valve plunger 363 upwardly and to reseat the valve 371, blocking communication be-

tween the chamber 307 and the drain. When the communication is blocked, inflowing liquid passing the fixed orifice 314 is no longer able to escape through the adjustable orifice 363, the chamber 307 is refilled with pressure fluid, and since the area exposed thereto on the side of the piston 309 is greater than that exposed to the pressure within the conduit 301, the valve 311 is reclosed at a rate established by the size of the fixed orifice 314.

During its closing movement, the valve 311 causes re-translation of the rack tube 324 back toward its original position, ultimately releasing the lever 351, which is restored to its latched position by the spring 354 as soon as the solenoid 331 is reenergized upon restoration of power, and rocks the lever 338 about the pin 362 as a pivot, simultaneously tensioning the relatively weak spring 336 and also recompressing the relatively strong spring 350. As the parts attain their closed position, the contacts 373 and 374 again come into abutment restoring all of the mechanism to its original condition ready for a subsequent surge preventing operation.

In this arrangement as well as in the preceding ones provision can readily be made for opening the main valve 311 in response to excessive pressure within the pipe line 301. That is readily effectuated in the present instance by connecting the pipe 313 through a duct 381 to a pressure responsive diaphragm 382, which moves in accordance with excessive pressure against the urgency of a spring 383, to open a valve 384 affording communication between the pipe 313 and a drain pipe 386, such connection being on the low pressure side of the restricted orifice 314. The size of the passage through the valve 384 is considerably in excess of the area for flow through the restricted orifice 314, so that when the valve 384 is opened in response to excessive pressure, the chamber 307 of the valve discharges its contents and the valve opens as previously described. When the excessive pressure is dissipated, the spring 383 is then permitted by the diaphragm 382 to reclose the valve 384 so that pressure fluid again refills the chamber 307, closing the valve at the predetermined rate.

I claim:

1. A surge preventer for use in a pipe line comprising a valve for releasing fluid from said pipe line, means responsive to pressure for urging said valve to open, superior means responsive to pressure for urging said valve to close, means responsive to an abnormal pressure in the pipe line for disabling said superior urging means, and means dependent upon said valve opening a predetermined amount for rendering said disabling means ineffective.

2. A surge preventer for use in a pipe line comprising a valve for releasing fluid from said pipe line, a differential piston and cylinder arrangement for operating said valve, means for supplying pressure fluid to exert a valve-opening pressure on one side of said differential piston, and means for varying the pressure on the other side of said differential piston including means for supplying pressure fluid thereto at a predetermined rate, means responsive to an abnormal pressure in the pipe line for releasing said pressure fluid therefrom at a greater rate, and means operated by said piston in full open position for rendering said releasing means ineffective.

3. A surge preventer for use in a pipe line comprising a valve for releasing fluid from said pipe line and adapted to move from a closed position

to an open position, means responsive to hydraulic pressure for urging said valve toward closed position, means operative upon occurrence of an increase in the pressure in said pipe line for rendering said hydraulic responsive means ineffective, and means operated upon attainment of open position by said valve for again rendering said hydraulic responsive means effective.

4. A surge preventer comprising a valve body and a valve adapted to occupy a closed position or an open position, means responsive to pressure for urging said valve from said closed position toward said open position, means for preventing said valve from moving from said closed position toward said open position, means responsive to an abnormal pressure for rendering said preventing means ineffective, and means operating when said valve is in said open position for again rendering said preventing means effective.

5. A surge preventer for use in a fluid pipe line in which pressure is maintained comprising a valve for releasing fluid from said pipe line and adapted to move from a closed position to an open position, a cylinder, a piston in said cylinder, means connecting said piston and said valve, means for subjecting a small area on one side of said piston to the pressure of fluid in said pipe line, means for subjecting a large area on the other side of said piston to the pressure of fluid in said pipe line, normally closed means for releasing fluid from said cylinder on said other side of said piston, means responsive to an abnormal pressure in the pipe line for opening said releasing means to effect opening movement of said valve, and means for reclosing said releasing means only upon attainment of open position by said valve.

6. A surge preventer for use in a fluid pipe line in which pressure is maintained comprising a valve for releasing fluid from said pipe line and adapted to move from a closed position to an open position, a differential piston connected to said valve and normally subjected on opposite sides to the pressure of fluid in said pipe line, means responsive to an abnormal pressure in the pipe line for releasing said pressure from one side of said piston to effect opening movement of said valve, and means for rendering said releasing means ineffective only upon attainment of full open position by said valve.

7. A surge preventer for use in a pipe line, comprising a normally closed valve adapted to be opened to release fluid from said pipe line, means responsive to an abnormal pressure in said pipe line for moving said valve to full open position, means for closing said valve and means operative by the movement of the valve to full open position for energizing said valve closing means.

8. A surge preventer for use in a pipe line, comprising a normally closed valve adapted to be moved from full closed position to full open position and back to full closed position, means responsive to pressure for moving said valve through said cycle of movement and means responsive to an increase in pressure in said pipe line for controlling said valve moving means.

9. A surge preventer comprising: a valve body having an inlet for connection to a pipe line, and an outlet for connection to a drain; a cylinder depending into said valve body; a cylindrical valve slidably within said cylinder and defining therewith a valve closing expansible chamber and a valve opening expansible chamber; means for subjecting both of said expansible chambers to

pipe line pressure; means responsive to an increase in the pipe line pressure for relieving the pressure within said valve closing expansible chamber; and means responsive to a predetermined expansion of said valve opening expansible chamber for disengaging said relieving means.

10. A surge preventer for use in a pipe line comprising: a valve for releasing fluid from said pipe line and adapted to move from a closed posi-

tion to an open position; first means responsive to the hydraulic pressure in said pipe line for urging said valve toward a closed position; second means responsive to an increase in the hydraulic pressure in said pipe line for rendering said first means ineffective; and third means operated by said valve when in said open position for rendering said first means again effective.

IRA MORGAN WHITE.
